Primary Examiner — Eric Goodman*Assistant Examiner* — Amy Wierenga(74) *Attorney, Agent, or Firm* — Troutman Sanders, LLP(57) **CLAIM**

We claim the ornamental design for a wireless device case, as shown and described.

DESCRIPTION

FIG. 1 is a left front side perspective view of the wireless device case;

FIG. 2 is a front side view of the wireless device case shown in FIG. 1;

FIG. 3 is a back side view of the wireless device case shown in FIG. 1;

FIG. 4 is a right side view of the wireless device case shown in FIG. 1;

FIG. 5 is a left side view of the wireless device case shown in FIG. 1;

FIG. 6 is a bottom view of the wireless device case shown in FIG. 1; and,

FIG. 7 is a top side view of the wireless device case shown in FIG. 1.

The broken lines depict portions of the wireless device case that form no part of the claim. The surfaces shown, including interior surfaces, form no part of the claim.
